UNITED STATES PATENT OFFICE.

JOHN S. BUCKWALTER, OF LANCASTER, PENNSYLVANIA.

CONNECTING-ROD STRAIGHTENING AND TESTING DEVICE.

Application filed March 27, 1922. Serial No. 547,059.

To all whom it may concern:

Be it known that I, JOHN S. BUCKWALTER, a citizen of the United States, residing at Lancaster, in the county of Lancaster and State of Pennsylvania, have invented certain new and useful Improvements in Connecting-Rod Straightening and Testing Devices; and I do declare the following to be a full, clear, and exact description of the invention, such as will enable others skilled in the art to which it appertains to make and use the same.

This invention relates to an improved connecting rod straightening and testing device and one object of the invention is to provide a structure of the character described so constructed that the connecting rod may be mounted above a base or platform with its bearing extending at substantially right angles to the base and to provide a gauge which rests upon but is unconnected with the base so that it may be brought into engagement with a wrist pin passed through the smaller bearing of the connecting rod and by being brought into engagement with the wrist pin above and below the smaller bearing, the angle of the wrist pin and bearing with respect to the horizontal base readily ascertained.

Another object of the invention is to so construct this device that the connecting rod may be mounted to extend substantially horizontal to the base with its bearings extending substantially in a vertical plane and the connecting rod securely held so that if it is found that the wrist pin passed through the smaller bearing does not extend at right angles to the horizontally disposed base, the connecting rod may be properly bent to position the wrist pin at right angles to the base.

Another object of the invention is to so construct the gauge used that the amount of adjustment necessary may be accurately registered.

Another object of the invention is to so construct the gauge that it may be provided with an indicator finger pivotally mounted and extending in operative relation to a scale and have its pivoted end portion provided with a heel extension engaging a feeler pivotally mounted and positioned in a vertical plane and having arm extensions for engaging the wrist pin above and below the smaller bearing.

Another object of the invention is to so

construct this device that the gauge will be strong and durable and consist of a comparatively few number of parts.

Another object of the invention is to so construct this device that the pivot post or cylinder about which the large bearing of the connecting rod is mounted will be removably held in engagement with the base thus permitting it to be removed and another put in its place in case the one already mounted upon the base is not the proper size to fit within the large bearing of the connecting rod to be tested.

This invention is illustrated in the accompanying drawings, wherein:

Figure 1 is a view showing the improved device in side elevation and a connecting rod in position for testing.

Figure 2 is a top plan view of the structure shown in Fig. 1.

Figure 3 is a sectional view taken along the line 3—3 of Fig. 2.

Figure 4 is a sectional view taken along the line 4—4 of Fig. 1.

Figure 5 is a sectional view taken along the line 5—5 of Fig. 1.

The base or platform 1 will be formed of cast metal or any other suitable material and will be provided with a flat upper face 25 extending in a horizontal plane when this base is placed upon a work bench or other support. Ears 2 have been provided so that fasteners may be passed through these ears and into the work bench to secure the base 90 in place upon the work bench and prevent it from slipping upon the bench when in use. This base is preferably recessed from its underface as shown in Fig. 3 so that a stem 3 may have its threaded lower end 95

portion screwed through a threaded opening 4 formed in the base and a locknut 5 screwed upon the lower end portion which protrudes as shown in Fig. 3. This locknut serves to prevent reverse rotation of the stem 3 after being screwed tightly into the opening 4. A sleeve or cylinder 6 which may be termed a pivot post fits loosely upon the stem 3 so that it can turn thereon and will be held in place by a washer 7 and 105 securing nut 8 which fits upon the threaded upper end portion of this stem 3 above the pivot post or cylinder 6. As previously explained, more than one of these cylinders 6 will be provided so that the proper cylinder may be put in place according to the size of the large bearing 9 which forms part 110

of the connecting rod 10 and is to be clamped about this cylinder. This connecting rod is of a conventional structure and has one end provided with the relatively large bearing 9 and its other end provided with the relatively small bearing 11 through which is to be passed the wrist pin 12. The wrist pin 12 when in place as shown in Fig. 1 should extend parallel to the cylinder 6 about which the large bearing 9 is clamped and since this cylinder 6 extends at right angles to the base 1, it will be readily seen that if the wrist pin when in place is found to extend at right angles to the base no adjustment nor straightening of the connecting rod is necessary, whereas if it is found that the wrist pin does not extend at right angles to the base when in place, then the connecting rod must be bent a sufficient amount to position the wrist pin at right angles to the base.

The gauge which is used to ascertain the angle of the wrist pin with relation to the upper surface of the base is in the form of a square having a lower base-engaging arm 13 and upstanding arm 14 which extends from one end portion of the lower arm 13 and is provided at its upper end with a head having scale markings thereon as shown at 15. The upstanding arm 14 is not as wide as the lower base-forming arm 13 and the end portion of the lower arm 13 is reduced in thickness to one side of the upstanding arm as shown at 16 so that the pointer 17 which extends longitudinally of the upstanding arm 14 and is pivotally mounted adjacent its lower end as shown at 18 may have swinging movement without the heel portion 19 striking the lower arm. The feeler 20 is vertically disposed and pivotally connected with the upstanding arm 14 in front of the pointer 17 and is provided with forwardly extending arms 21 for engaging the wrist pin above and below the relatively small bearing 11 at the free end of the connecting rod. The spring 22 which is carried by the upstanding arm 14 and engages the pointer 17 above the pivot pin 18 holds the heel 19 in engagement with the feeler and it will thus be seen that when the feeler is positioned to engage the wrist pin above and below the bearing 11, the angle of the wrist pin will be assumed by the feeler and the pointer will indicate upon the scale 15 the angular relation of the wrist pin and bearing 11 to the horizontally disposed upper face if the wrist pin and bearing 11 are positioned at a right angle with respect to the base the pointer will be at the center of the scale as shown in Fig. 1, whereas if the wrist pin is not at a right angle but slightly out of a perpendicular position, the pointer will indicate this by moving to one side or the other of the center of this scale marking. Swinging movement of the feeler is limited

by the pin 23 which extends through the slot 24 of the feeler below the pivot pin 25 and swinging movement of the pointer is limited by pins 17' which extend from the side portions of the upstanding arm 14. 70

When this device is in use, the connecting rod which is to be tested will be put in place and have its large bearing 9 clamped about the pivot post or cylinder 6. The wrist pin 12 will be put in place and the gauge or square as it may be termed, will then be placed upon the base 1 and moved upon the base so that the arms 21 of the feeler 20 will engage the wrist pin above and below the bearing 11. If it is found that the pointer 17 is positioned at the center of the scale markings 15, then no adjustment is necessary but if it is found that the pointer extends to one side or the other of the center of this scale than the connecting rod will be bent until the pointer assumes the position shown in Fig. 1. After proper adjustment has been made with the gauge positioned as shown in Figs. 1 and 2, the gauge will then be moved around to one side or the other of the connecting rod and the arms of the feeler again brought into engagement with the upper and lower end portions of the wrist pin. The position of the pointer with respect to the scale will then be observed and if necessary proper adjustment made. It will thus be seen that with this device, the connecting rod can be very easily and quickly tested to see if the bearings 9 and 11 are in proper relation to each other. 100 After the connecting rod has been tested and straightened if necessary, it will be removed and another put in place or the device put away until again to be used. If it is found that the next connecting rod does not fit properly upon the cylinder 6 which is in place, this cylinder will be removed and one of a proper size substituted for the one already in place. 110

I claim:

1. In a connecting rod straightening and testing device, a base having a plane horizontal surface, a pivot post projecting therefrom at a right angle, said post being adapted to hold the connecting rod by one of its bearings, and a gauge resting on the surface of said base and including a horizontal arm and a vertical arm, the vertical arm being provided with a scale, a pointer pivoted to said vertical arm and co-operating with said scale, and an upright pivoted beam pivotally connected with the vertical arm and contacting with said pointer. 115

2. In a connecting rod straightening and testing device, a horizontal base with a plane horizontal surface, a cylinder projecting from said base at right angles to said surface, and a gauge resting on the surface of said base and including a horizontal arm and a vertical arm, the vertical arm being 120

provided with a scale, a pointer pivoted to said vertical arm and co-operating with said scale, and an upright pivoted beam pivotally connected with the vertical arm and 5 contacting with said pointer.

3. In a connecting rod straightening and testing device, a horizontal base having a plane surface, a pivot post projecting from said plate at right angles to the plane 10 surface thereof and adapted to hold a connecting rod by one of its bearings, and a gauge

for resting upon the plane surface of said base and including an upright arm, an indicator movably connected with said upright arm, and a feeler movably connected with 15 the upright arm for operative engagement with said indicator and operative engagement with a pin fitted in the other bearing of the connecting rod.

In testimony whereof I have hereunto set 20 my hand.

JOHN S. BUCKWALTER.
